UNITED STATES PATENT OFFICE.

JULIUS S. MEYER, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 15 180, dated July 29, 1884.

Application filed January 25, 1884. Term of patent 14 years.

To all whom it may concern:

Be it known that I, JULIUS S. MEYER, of New York city, New York, have invented a new and original Design for Carpets, of which the following is a specification, reference being had to the accompanying photograph, which forms a part of the same.

The invention relates to a design to be worked into or upon surfaces—such as carpets or similar fabrics; and it consists in the novel configuration and grouping of figures, herein specifically shown and claimed.

The accompanying photograph is a face view of a carpet showing my new design.

15 The design consists of four large flower groups, A, B, C, and D. Interspersed in the open spaces between these groups are various small disconnected groups of minute geometric work and several squares and octagons variously ornamented. These do not belong to the flower groups, but constitute a background for the same.

20 The group A (shown in the lower center of the photograph) consists of a central flower-and-leaf mass having projections of flag-like leaves above and blossoms and leaf sprays on both sides. It abuts below against an ornamented square, represented as supporting the group, and which forms part of the group A.

25 The group B (shown in the upper center of the photograph) is the largest group of the design. It consists of a large central mass of open flowers and leaves, and has blossoms and fern sprays projecting on all sides. On the left below there is a blossom spray; on the 30 right below two fern sprays. The group terminates above in a blossom spray on the left, and a fern spray drooping over toward the right.

The group C (shown at the right center and at the left upper and lower corners of the photograph) is a smaller leaf mass with blossom sprays above. To the left above is a cluster of flag-like leaves having a single star-shaped flower. Abutting against the group below and forming part of it is an ornamented rectangular figure.

The group D (shown at the left center and at the right upper and lower corners of the photograph) is characterized by projecting buds and sprays of geranium-leaves. To the left above are three flower-stems with drooping heads; to the left below a small spray of flag-like leaves, and to the right below a spray of fern. To the right above is a blossom spray carrying four large blossoms.

I claim—

1. The design for a carpet, consisting of the group A, substantially as shown and described. 60
2. The design for a carpet, consisting of the group B, substantially as shown and described.
3. The design for a carpet, consisting of the group C, substantially as shown and described. 65
4. The design for a carpet, consisting of the group D, substantially as shown and described.
5. The design for a carpet, consisting of the groups A, B, C, and D and the intervening figures, substantially as shown and described. 70

JULIUS S. MEYER.
